PARKING LOT METER

Lewis G. Wilkin, Cincinnati, and Richard F. Spiller, Urbana, Ohio; said Spiller assignor to said Wilkin

Application August 18, 1949, Serial No. 4,585

Term of patent 14 years

(Cl. D52—3)

To all whom it may concern:

Be it known that we, Lewis G. Wilkin and Richard F. Spiller, residing, respectively, at Cincinnati, Hamilton County, State of Ohio, and Urbana, Champaign County, State of Ohio, have invented a new, original, and ornamental Design for a Parking Lot Meter, of which the following is a specification, reference being had to the accompanying drawing, forming a part thereof. In the drawing,

Figure 1 is a view in elevation showing the appearance of the opposite faces of a parking lot meter, embodying our new design;

Figure 2 is a view in elevation showing the appearance of the opposite sides of the meter; and

Figure 3 is a top plan view of the meter.

We claim:

The ornamental design for a parking lot meter, as shown and described.

LEWIS G. WILKIN.
